[57] ABSTRACT

A cellulose digesting apparatus having at least one vertical digester in open communication with a pressure-resistant vessel containing a screening device, the screening device comprising a shell having an upper impervious portion and a lower strainer portion, wherein liquid is strained from a chips-liquid suspension for recirculation of the liquid, and a feeding device which is adapted to transfer the chips from said vessel to the digester, around the shell a circular trough for collecting chips discharged over the top edge of the impervious portion, the feeding device comprising a plurality of chips outlets in the vessel each adapted for connection to a separate digester and a distributing device for the distribution of the chips upon the outlets used.

A SCREENING AND FEEDING DEVICE FOR CELLULOSE DIGESTERS

This application is related to U.S. Ser. No 339,761 filed Mar. 12, 1973 by Oliver Laakso.

The invention relates to cellulose digesting apparatus for the charging of chips to a digester which is in open communication with a separate pressure-resistant vessel containing a screening device which strains a chips-liquid-suspension in order to recycle the liquid, and a feeding device for the transfer of the chips from said vessel to the digester. An example of a digester is shown in the U.S. Pat. No. 3,429,773.

The invention is concerned with the problem that cellulose mills often are in continuous expansion, and therefore, after only a few years production, a new digesting plant may have to be increased in capacity. An object of the invention is to effect in a simple manner and at a comparatively small cost, a desired expansion so that cellulose digesting plants can be expanded with the greatest possible use of the equipment already installed, i.e. with as little rebuilding thereof as possible. Thus, the invention is directed at using the installed devices for pretreatment of the chips and transportation thereof to the digester top; if at a later stage it is desired to enlarge the digesting plant with one or more further digesters, only simple modifications need be made. These objects are achieved by providing a pressure-resistant vessel with a plurality of chips outlets, each adapted for connection to a separate digester, allowing the plant to be supplemented with one or more additional digesters. Further, a device is provided for the proper distribution of the chips into the outlets employed. According to a preferred embodiment, the upper end of a vertical cylindrical separating shell surrounds a feeder screw coaxial therewith, and feeds the chips upwardly. This upper end is surrounded by a portion of the pressure vessel preferably forming a circular trough with downwardly sloping chips outlet tubes being connected to the bottom of said trough at a level lower than the upper edge of said separating shell, so that chips flowing over said edge are transferred to the digester or digesters substantially by the action of gravity.

BRIEF DESCRIPTION OF THE DRAWINGS

The preferred form of the invention will now be described more particularly with reference to the accompanying drawings wherein:

FIG. 1 diagrammatically shows a cellulose digesting apparatus comprising two digesters,

FIG. 2 is a vertical elevational and partially cross-sectional view shown at an enlarged scale, of the screening and chips distributing vessel forming part of said apparatus;

FIG. 3 is a modified form of the invention shown in FIGS. 1 and 2, FIG. 4 is a partial cross-sectional view taken along lines 4-4 of FIG. 2, with chips removed, showing exemplary displaceable lids for varying the size of the chips outlets.

DETAILED DESCRIPTION

The apparatus in FIG. 1 comprises two vertical essentially cylindrical continuous digesters 11, 13, the upper ends of which are continuously fed with a mixture of chips and digesting liquor. From the lower ends of the digesters 11, 13 digested and partially washed cellu-

losic pulp is continuously discharged. The term "chips" is meant to include not only cellulosic fiber materials such as hewn wood chips but also other finely comminuted fiber material, such as straw, bagasse, reed, etc.

5 The digesting liquor may be of any kind, such as sulphate, sulphite, or soda liquor.

The chips are pretreated and distributed to each of the digesters. Chips from chips bin 15 are fed in the usual manner through a low-pressure valve 17 into a 10 steaming vessel 19 wherein the chips are steamed with low-pressure steam. By means of a high-pressure transfer valve 21 the chips are then transferred to a conduit 23 filled with the digesting liquor at approximately the digester pressure. The conduit 23 is connected to a vertical, conical impregnating vessel 25 whose circumference increases with its vertical longitudinal axis. The vessel 25 is united with the pressure-resistant vessel 27 which encloses a screening device and a chips distributing device. Liquid screened off by said screening device 20 in vessel 27 is returned through the conduit 29 to the high-pressure transfer valve 21. Pump 31 circulates the liquid in a loop over 21, 23, 25, 27, and 29. In said loop the chips are introduced by means of the valve 21 so that the chips suspended in the liquid are flushed into the vessel 27 situated at the level of the digester tops and are delivered and retained therein, whereas the liquid of the suspension is separated and recirculated.

The vessel 27, shown partially in sections in FIG. 2, is provided within a pressure-resistant casing 33 and a 30 vertical cylindrical separating shell 35 of the same diameter as and forming an extension of the upper end of the impregnating vessel 25. The lower end of the separating shell 35 is perforated or shaped with slits so as to form a strainer, whereas the uppermost portion of the separating shell is impervious and forms a partition. Inserted into the shell is a feeder screw 37 attached to a vertical shaft 39 which extends through and is sealed to the lid 41 of the casing 33. A motor 42 (FIG. 1) connected to the exterior end of the shaft 39 turns the 35 feeder screw 37 causing the chips-liquor-suspension to move upwardly within the separating shell 35. Excess digesting liquor is drained through the straining apertures of the shell into the space between the shell 35 and the casing 33 and then into the conduit 29 back to the high-pressure transfer valve 21, whereas the chips are raised over the edge 43 of the shell 35. Usually a free liquid surface is maintained at a level 45 within the impervious upper portion of the separating shell. When the chips have been raised above said level, entrained 40 digesting liquor drains off, so that the chips traveling over the edge 43 merely contain digesting liquor absorbed in the pores of the fiber material or superficially adhered thereto.

50 Vessel 27 forms a steam-filled space, surrounding the upper edge 43 of the separating shell, the lower boundary of which forms a circular launder or trough 47. Said trough 47 extends around the upper edge 43 of the separating shell 35 and has its bottom situated at a lower level than said edge, so that chips fed upwardly through the shell by means of the feeder screw 37, drop over the edge 43 down into the trough 47 by gravity. Connected to the bottom of the trough are at least two downwardly sloping chips outlet tubes 49, 51, which by means of connecting tubes 53 and 55 may be connected to the 55 separating digesters 11 and 13. Said tubes form an open communication between the vessel 27 and the respective operating digester, but it may be advantageous to

insert shut-off valves in the conduits 53, 55 in order to be able to operate one digester without interruption when the other is temporarily taken out of operation.

According to the invention, the vessel 27 is provided with a device for distributing the chips upon the chips outlets 49, 51. In the embodiment shown in FIG. 2 said distributing device consists of a scraper attached to the shaft 39 which comprises scraper arms 57 projecting radially across the edge of the shell 35 and down into the bottom of the trough 47. Chips that drop over the edge 43 down into the trough 47 are collected by said rotary scraper arms and are carrying along until they drop into the chips outlet tubes 49, 51. With diametrically opposite locations of two outlets the chips will be distributed into equal parts into each outlet. When the digesters are of different sizes or capacities so that distribution of the chips may be required in different proportions, the location of the outlets on the periphery may be changed accordingly. If, for example, one digester requires twice as many chips as the other, the outlets are placed at an angle of 120 degrees from each other, whereby the scrapers collect and transfer to the smaller digester the chips which have dropped into one third of the circumference of the trough, and collect and transfer to the larger digester chips which have dropped into the remaining two thirds of the circumference of the trough. Obviously, the desired distribution may also be attained by varying the size of the outlets. Variations of both size and angle can be brought about by displaceable lids, such as lids 50 shown in FIG. 4, in the bottom of the trough 47.

The drawings refer to an apparatus comprising two digesters, but the apparatus may be operated with a single digester, as is shown in FIG. 2 by the digester 13 with dash lines. In this latter case the chips outlet 51 is blocked, e.g. by means of a blind flange at its lower end, and the scraper arms 57 are not used for their distributing function but merely for moving the chips in the trough to the single outlet 49.

Of course, the number of chips outlets may be increased and it is possible to use a distributing vessel with three, four or more chips outlets that are used according to the total required output of the digesting apparatus.

The entire quantity of digesting liquor required for the digestion is supplied through the conduit 61 and high-pressure pump 63 after having been mixed with the liquor transferred to the low-pressure side of the transfer valve 21, which is returned via the screening device 65 and the tank 67. A portion of the liquor supplied is transferred into the conduit 29 by the valve 69 which is controlled by the level 45 in the vessel 27 so as to maintain said level, whereas the remaining portion of the liquor supplied is pumped through the conduit 71 directly to the digester tops and distributed by means of the valves 73, and 75. Preferably, said liquor portion is introduced into the conduits 77 and 79 along with pressure steam to the digesters for heating the chips therein to digesting temperature. In this manner the liquor will be atomized and sprayed as a mist over the chips in the digester tops.

As an alternative, all digesting liquor may be supplied to the vessel 27. This is preferred when the chips are able to absorb a sufficient quantity of liquor, so that a free liquor level 45 will be maintained below the edge of the straining portion of shell 35 without requiring

any particular level control. On the other hand, if the liquor is to flow over that edge 43, procedures should be taken to distribute the liquor properly into the digesters.

5 The above-described embodiment merely constitutes an example of the application of the invention and may be modified as to its details within the scope of the following claims. Thus the apparatus can also be operated when the digesting liquor or the main part thereof is 10 supplied directly to the digesters and such liquid as is required for suspending the chips and flushing them to the digester tops consists of water, as is the case in prehydrolysis digesters, or of more or less diluted white liquor or black liquor.

15 In another embodiment of the invention shown in FIG. 3, the inlet to the bottom of the vessel 27 has been modified by the addition of a chamber 26 and secondary scraper 28. The section 26 effectively increases the total volume of pipe 25 thereby providing for a 20 longer retention time of the chips in the feeding line; that is, chips are impregnated in liquid at full digester pressure.

25 The chamber 26 may be a conical pipe connection and 28 is a rotating scraper body which will facilitate the chip movement from the larger pipe to the smaller diameter entrance 38. The scraper rotates together with screw 37. The lower end of the screw shaft of FIG. 2 may have a downwardly pointing conical nose to decrease the resistance against the chip flow. However, 30 by providing a larger feeding pipe as in 25-26 of FIG. 3, the cone can be omitted and the scraper 28 substituted by coupling the screw 37 to the scraper shaft. The scraper itself can be supported by the bearings in the 35 bearing housing which in turn is supported by arms fastened to pipe connection 26.

What is claimed is:

1. A cellulose digesting apparatus in which a top portion of at least one vertical digester is in open communication with a pressure-resistant vessel containing a screening device wherein liquid is strained from a chips-liquid suspension for recirculation of the liquid, and a feeding device for transferring the chips from said vessel to the digester, said feeding device comprising a plurality of chips outlets in the vessel each for connection to a separate digester and a distributing device for the distribution of the chips upon the outlets used, said screening device comprising a separating shell having an upper impervious portion and a lower strainer portion including means for collecting liquid separated from the chips; means for feeding the strainer chips upwardly through the shell for discharge over the top edge of the upper impervious portion, said means including a feeder screw surrounded by said shell and coaxial therewith; collecting means around said shell and below the top edge of said impervious portion for collecting strained chips discharged therefrom, said collecting means comprising a circular trough; the chips outlets comprising tubes connected to and sloping downwardly from the bottom of said trough for discharge into said digestors substantially by gravity.

65 2. Apparatus according to claim 1 wherein the distributing device comprises one or more scraper arms extending radially beyond the separating shell into the circular trough and being attached to and driven with the feeder screw.

3. Apparatus according to claim 2 wherein the outlets are varied with respect to position about the trough so as to vary proportions of chips input into said outlets.

4. Apparatus according to claim 1, which further includes an impregnation vessel coupled to the pressure-resistant vessel which is adapted to impregnate the chips therein with digesting liquor at essentially the pressure of the digester.

5. Apparatus according to claim 4 wherein said distributing device comprises a first scraper and wherein the lower portion of the pressure-resistant vessel has a

lower opening therein and the impregnation vessel includes a frusto-conical section coupled to the pressure-resistant vessel at its lower opening; the top of the impregnation vessel has a second scraper in the frusto-conical section which includes radially extending arms coupled at a center hub and driven by the feeder screw.

6. Apparatus according to claim 1 further comprising means for varying the size of the chips outlets to effect a desired distribution of chips to chips outlets.
